UNITED STATES PATENT OFFICE.

JOHN E. W. FOGAL, OF QUINCY, ILLINOIS, ASSIGNOR TO QUINCY ELEVATOR GATE COMPANY, OF QUINCY, ILLINOIS.

OPERATING MEANS FOR ELEVATOR SHAFT AND CAR DOORS.

1,225,606.

Specification of Letters Patent.

Patented May 8, 1917.

Application filed September 9, 1916. Serial No. 119,249.

To all whom it may concern:

Be it known that I, JOHN E. W. FOGAL, a citizen of the United States, and a resident of Quincy, in the county of Adams and State of Illinois, have invented a new and Improved Operating Means for Elevator Shaft and Car Doors, of which the following is a full, clear, and exact description.

This invention relates to apparatus for operating the gates or doors at the floors of an elevator shaft after the method disclosed in United States Letters Patent 865,335, granted to me September 3, 1907; and the present invention relates to improvements in apparatus of this character.

The invention has for its general objects to improve the construction and operation of door-operating mechanisms so as to be reliable and efficient in use, comparatively simple and inexpensive to manufacture and install, and so designed as to afford maximum safety.

A more specific object of the invention is the provision of an electromechanical apparatus for opening and closing elevator or hatch doors according to the will of the operator, the apparatus including means whereby the power for moving the car is cut off as long as the gate or door is open, so that the operator must see to the closing of the door before starting the car.

Another object of the invention is the provision of a door or gate for the car which is operatively connected with the means for opening and closing the hatch or shaft doors, so that the car door or gate and the selected shaft door or gate will open or close simultaneously.

An additional object is the provision of a car door or gate which is operatively connected at all times with a pull cable installed in the shaft, so that a pull thereon will operate through a suitable sheave and cable system to open or close the gate of the car.

The invention has as a further object to provide a motor-driven winding drum on which the pull or gate-operating cable is adapted to wind and unwind, in combination with a brake device for the motor under the control of the operator in the car,

and means automatically controlling the setting of the brake device to stop the motor when the cable has been wound or unwound a predetermined amount for effecting the opening or closing of the doors or gates.

Further, the invention provides a novel operating means between the brake device and the controller for the motor, whereby the operator will, upon actuating the controlling cable, cause the brake device to first release before the switch is closed to supply power to the motor, there being also means whereby the power will be automatically cut off when the gates or doors have reached their open or closed position, and this cutting off of the power takes place just prior to the automatic setting of the brake device.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention and wherein similar characters of reference indicate corresponding parts in all the views.

Figure 1 is a vertical section of an elevator shaft with intermediate portions broken away, showing the car at one of the floors and the car gate and hatch door in closed position;

Fig. 2 is a vertical sectional view on the line 2—2, Fig. 1;

Fig. 3 is a plan view of the electromechanical gate-operating apparatus with the quick-acting reversing switch in section;

Fig. 4 is a side view of Fig. 3;

Fig. 5 is a vertical sectional view on the line 5—5 Fig. 4;

Fig. 6 is a sectional view on the line 6—6;

Fig. 5;

Fig. 7 is a sectional view on the line 7—7;

Fig. 5;

Fig. 8 is a sectional view on the line 8—8;

Fig. 7;

Fig. 9 is a view of the brake and its operating cam;

Fig. 10 is a sectional view of the inter-

locking switch for holding off the power for moving the car while the gate or door is in open position;

Fig. 11 is a diagrammatic view of the 5 electric circuits of the motor and the control switch therefor;

Fig. 12 is a vertical section of an elevator shaft with a modified form of car gate-operating means;

Fig. 13 is a vertical section on the line 10 13—13, Fig. 12; and

Fig. 14 is a side view of an elevator car with another form of gate-operating means.

To avoid confusion the hoisting means 15 for the elevator car has been omitted from the drawings, but it is to be understood that any approved means may be employed for this purpose. A designates an elevator shaft which is provided with door openings 1

20 at the various floors 2, and at each opening 1 is a door or gate B of any approved design. In the present instance the door B is of the flexible winding or rolling type and winds on a roller 3 mounted in a box 25 4 at the top of the door opening, the door winding in opening and unwinding in closing. The elevator car C moves on the usual guide rails 5 and is equipped with the usual means for raising and lowering it.

30 The car may have one or more sides open but in the present instance the car is shown with one side open and provided with a vertically movable gate D, as shown in Fig. 2. This gate provides extra safety and must

35 be closed before the car can be started, and consequently it is impossible for a box, truck or other article to project outwardly beyond the car floor far enough to contact with the floor projections while the elevator

40 is moving up or down in the shaft, and the gate or door D also prevents persons from falling against the shaft wall or doors or from extending the foot beyond the car line. The shaft doors are adapted to be controlled

45 by the operator of the car so that when any floor is reached the operator can cause the shaft door at such floor to be opened. The construction for accomplishing this is set forth in my prior patent hereinbefore referred to, so that only a brief description of

50 the shaft door-operating means need be given. The operating means for the car gate or door is so related to the shaft door-operating means that the opening and

55 closing of the doors or gates occurs simultaneously and under only one voluntary act of the operator. A vertical, movable bar 6 extends the full length of the shaft and is suspended by a pull cable 7 connected

60 with the upper end of the bar and guided over pulleys p and p' at the top of the shaft, and from this point the cable 7 passes downwardly to a winding drum 8 at the bottom of the shaft, so that by the turning

of the drum the cable 7 will wind thereon. 65 At each floor or at each shaft door the bar 6 has a slot 9 into which is engageable a pawl 10 mounted on a crosshead or slide 11, such slide being connected with a cable 12 that passes around a stationary guide pulley 13 in the elevator shaft, and which is connected with a winding drum 14 of the roller 3 of the adjacent door B, as shown in Fig. 1. A shoe on the car (not shown) presses the pawl 10 into the slot 9, and when the 75 car reaches the desired floor, the operator in the car pulls the controlling cable 15 so that the cable 7 will be wound on the drum 8 and cause the bar 6 to move upwardly, which operating through the pawl 80 10 and carriage 11 will cause the door B to open. When the door is fully open, the turning of the winding drum 8 automatically stops by means hereinafter to be explained. Obviously, by turning the drum 8 in the 85 opposite direction the cable 7 unwinds therefrom and allows the bar 6 to drop, so that the door B will automatically close. The controlling element 15 is an endless rope or cable having one flight extending vertically 90 through the car, and this cable is guided around a pulley 16 at the top of the shaft and around a pulley 17 at the bottom of the shaft, which latter pulley is operatively connected with a controller for the mechanism that operates the winding drum 8. 95

The car gate D is raised and lowered by a cable 18 that extends upwardly from the center of the gate to an overhead pulley 19 mounted on a cross-piece 20 that is fastened 100 on the corner posts 21 of the gate, and from this pulley 19 the cable extends laterally to a guide pulley 22 on one of the gate posts, and from this pulley 22 the cable extends downwardly to and around a pulley 23 fastened to the outside of the car body adjacent the bottom thereof, as shown in Fig. 1. This pulley has a stationary axis and the cable passes upwardly to and over a pulley 24, and thence downwardly therefrom, 110 where the cable is anchored at 25 on the car body. The pulley 24 moves up and down with respect to the pulley 23, and consequently exerts a longitudinal pull on the cable 18 to raise the gate D when the pulley 115 24 moves upwardly, and when the pulley moves downwardly the gate closes under its own weight. The movement of this pulley 24 is under the control of the operator in the car and is operatively connected with 120 means installed in the shaft, so that the gate can be opened at any time irrespective of the position of the car. For this purpose a cable 26 extends vertically of the shaft, with the lower end anchored at 27, and the upper 125 end of this cable passes around pulleys 28 and 29 and connects with the cable 7 at 30, so that the cable 26 will move with the latter.

- On the side of the car body is a large sheave or pulley 31 turning on a fixed axle 32 and directly under this sheave 31 is another sheave 33 which is connected by a hanger 5 or frame 34 with the sheave or pulley 24, and the sheave 33 is movable along the vertical guideway 35 on the side of the car. The cable 26 extends upwardly past the sheave 33 and around the top of the sheave 10 and thence extends downwardly to and under the sheave 33, and from this point it continues to the top of the shaft or to the pulley 28. In other words, the cable 26 has a loop extending around the sheaves 31 15 and 33. By this arrangement the car has a permanent running engagement with the cable 26, and when the cable is pulled upwardly, as when the cable 7 is wound on the drum 8, the sheave 33 is moved upwardly 20 toward the sheave 31, and consequently the cable 18 is actuated to open the gate D. By the arrangement shown a pull of eight feet on the cable 7 will move the sheave 33 upwardly four feet, but this reduced movement 25 is multiplied by the differential cable and pulley system connected with the gate D. In other words, the movement of the sheave 24 upwardly four feet will produce a movement of eight feet of the gate D.
- 30 Another system of pulleys and cables for transmitting power to the gate is shown in Figs. 12 and 13. The cable 26' corresponding to the cable 26, Fig. 1, has its lower end connected at 35 with the bottom of the car 35 and passes downwardly to and under a guide pulley 36 in the bottom of the shaft, thence upwardly to and over a pulley 37 mounted on a carriage 38 which slides in a guideway 39, and from the pulley 37 the cable 26' extends downwardly to and under a pulley 40 mounted in a carriage 41 slideable in a guideway 42 on the side of the car C', and from the pulley 40 the cable 26 extends upwardly to the top of the car, 40 where it is connected at 43 therewith. The pulley 37 is moved upwardly by a connecting cable 26^a which connects with the shaft-gate-operating or pull cable 7'. The carriage 41 is connected with a cable 18' that 45 passes around a pulley 44 fixed on the side of the car, and from this point the cable 18' extends upwardly to suitable guide pulleys and is connected with the gate D', as shown in Fig. 13. Obviously, when the cable 7' 50 is wound on the drum 8', the cable 26' raises the pulley 40, which in turn exerts a pull on the cable 18' and causes the gate D to open. If desired, the various sheaves or pulleys 55 can be arranged at the sill of the car C', as shown in Fig. 14, in which 26^a corresponds to the cable 26, Fig. 1. This cable passes around guide pulleys 45 and 46 and also around a pulley 33^a which moves horizontally toward and from the pulleys 45 and 46.
- This pulley 33^a is connected with a pulley 24^a 65 which operates on a cable 18^a to raise or lower the gate of the car.
- The electromechanical apparatus E for operating the cable 7 may be mounted either at the bottom or top of the shaft. In the 70 present instance this apparatus is shown outside the elevator shaft at the bottom thereof, and the shaft 45 extends through an opening 46 in the wall 47 of the elevator shaft and has fastened thereto the winding 75 drum or wheel 8. The shaft 45 is provided with a worm wheel 48 disposed in a casing 49, and meshing with this worm wheel is a worm gear 50 on a shaft 51. This shaft 51 is connected with an electric motor 52, 80 which, together with the gear casing 49, is mounted on a bed 53. On the shaft 51 is a brake wheel 54 with which engage brake shoes 55. These shoes are pivoted at 56 on the bed 53 and their free extremities are 85 formed with parallel lugs 57 carrying frictionless rollers 58. The brake shoes are urged into frictional engagement with the wheel 54 by springs 59 which are supported on a rod 60 which passes through the lugs 57. On this rod are nuts 61 for adjusting the tension of the springs, which latter bear against the outer faces of the lugs to urge the latter toward each other. The rollers 58 engage opposite faces of a cam wheel 90 95 62 fastened to a controller shaft 63 that extends through an opening 64 in the wall 47 of the elevator shaft, and on the inner end of the shaft 63 is the wheel 17, around which the controller cable 15 passes. The cam wheel 62 has a reduced portion 65, and when the rollers 58 are engaged with this reduced portion 65, the brake shoes are set 100 into frictional engagement with the wheel 54, so that the motor shaft will be held 105 against rotation. Sloping surfaces 66 are provided between the reduced portion 65 and the wide portion of the cam wheel, so that as these beveled surfaces pass between the rollers 58 there will be a gradual application or release of the brake shoes.
- The cam-carrying shaft 63 also serves as 110 means for actuating the quick-acting reversing switch F, which is mounted within a box 67 carried on the bearing pedestals 68 for the controller shaft 63. The switch F comprises a shaft 69 carrying a plurality of contacts 70 which coöperate with a plurality of sets of fingers 71. In line with the shaft 69 is a crank shaft 72 which carries a disk 73 adjacent the disk 74 on the contact-carrying shaft 69. A helical spring 75 is coiled on the inner end of the shaft 72, and the ends of the springs are bent outwardly into members 76 and 77 which are engageable respectively by lugs 76^a, 76^b and 77^a, 77^b, lugs 76^a and 77^a being arranged on the disk 73, 115 and the lugs 76^b and 77^b being arranged on
- 120
- 125

the disk 74. The disk 74 has in its periphery a plurality of spaced recesses 78, 79 and 80, and bearing on the periphery is a roller 81 mounted on an arm 82 which is 5 fulcrumed at 83 and backed by a spring 84 that urges the roller against the disk or wheel 74. When the roller is engaged with the central recess 79, as in Fig. 7, the switch contacts are in open-circuit position, as 10 shown in Fig. 6, but when the disk 74 has turned so that the roller engages in either recess 78 or 80, the switch contacts will be in closed-circuit position for the forward or reverse rotation of the motor 52, to effect 15 the opening or closing movement of the gates or doors of the elevator car or shaft. The yielding lock formed by the spring-pressed roller 81 prevents the switch shaft from turning until the spring 75 is placed 20 under a tension by the turning of the shaft 72 sufficient to overcome the yielding power of the roller 81, and when this occurs the tension of the spring 75 causes a quick movement of the switch shaft, which movement is 25 arrested by the roller 81 entering either recess 78 or 80, when the switch will be in closed-circuit position. The crank shaft 72 associated with the switch is operated by a suitable connecting means between such 30 shaft and the controller or cam-carrying shaft 63. On this shaft is a wheel 85 which has a stud 86 rotatably mounted thereon, and projecting from one side and passing transversely through this stud is a rod 87 35 hingedly connected at 88 with the extremity of the crank arm 89 on the shaft 72. On the rod 87 is a helical compression spring 90 which has its upper end engaging a collar or shoulder 91 on the rod 87, and the lower 40 end of this spring is adapted to engage the stud 86. Under the stud 86 and fastened to the rod 87 is a collar 93 separated from the stud 87 by a slight clearance, so that as the wheel 75 turns to the right or left, Fig. 4, 45 the rod 87 will swing on the pivot 88 as a center until the stud 86 moves into engagement with the collar 93, and then the stud 86 will, by engaging the collar 93, move the rod 87 downwardly to the right or left, as 50 indicated by the arrows, to throw the switch to closed-circuit position. This lost-motion connection between the wheel 85 and rod 87 allows for a limited rotation of the controller or cam-carrying shaft sufficient to 55 release the brake shoes 54 from the brake wheel before the motor circuit is closed. In other words, the brake will be released before the motor starts to operate. When the switch is in closed-circuit position and it 60 is to be open-circuited, the wheel 85, Fig. 4, turns to the right or left to throw the stud 86 from either dotted-line position to the central full-line position. In doing this the spring 90 is first compressed and placed 65 under tension, and when the roller 81, Fig. 6, releases from either recess 78 or 80, the movable switch contacts will be quickly thrown to open-circuit position, assisted by the expansion of the spring 90, and this occurs before the wheel 85 completes its return movement or before the cam wheel 62 permits the brake shoes to set and stop the motor. In other words, the current is cut off from the motor before the brake device 70 stops the motor shaft from turning. 75

A switch G is employed for the purpose of cutting off the power automatically from the elevator car when the door or gate opens, so that the car cannot be started unless the gate is closed. The switch G 80 comprises contacts 95 and 96 and a bridging contact 97, which, when engaged as shown in Fig. 10, permits the elevator car to be electrically raised or lowered by the usual electrical apparatus. The bridging contact 97 is fastened to a lever 98 fulcrumed at 99, and on the lever is a wheel 100 which is engaged with a disk 101. This disk is mounted on an extension 45^a of the shaft 45, Fig. 3, there being a thread 102 on the shaft extension with which the disk 101 is engaged so that, by the turning of the shaft, the disk 101 will move between the spaced stops 103 and 104 fastened to and 85 rotatable with the shaft. When the disk 101 is in its outermost position, as shown in Figs. 3 and 10, the switch G is in closed-circuit position, and when the shaft 45 turns, the disk 101 moves inwardly and 90 opens the switch G by moving the bridging contacts 97 out of engagement with the contacts 95 and 96. The disk 101 is provided with a sprocket wheel 105 with which 95 engages a sprocket chain 106, and this in turn 100 engages sprocket teeth 107 on the wheel 85. The disk 101 is adapted to be clutched to the shaft 45 by means of clutch teeth 108 on the hub of the disk 101 and corresponding shoulders 109 on the stops or collars 103 and 104. By this means the shaft 45 105 will operate through the sprocket and chain connection to turn the cam-carrying shaft, whereby the latter will cause the brake to set and stop the motor automatically when the disk 101 reaches the limit of its movement in either direction, which limit is 110 reached when the elevator door or gate reaches its open or closed position. 115

From the foregoing description taken in connection with the accompanying drawings, the advantages of the construction and method of operation will be readily understood by those skilled in the art to which the invention appertains, and while I have 120 described the principle of operation, together with the apparatus which I now consider to be the best embodiment thereof, I desire to have it understood that the app 125

paratus shown is merely illustrative and that such changes may be made when desired as fall within the scope of the appended claims.

5 Having thus described my invention, I claim as new and desire to secure by Letters Patent:

1. An elevator shaft, a car movable therein, a gate for the car, an element extending up and down the shaft and capable of movement independently of the car, and means on the car and having a running connection with the said element for receiving motion therefrom when the element is moved to 15 open and close the gate.

2. An elevator shaft, a car movable therein, a gate for the car, an element extending up and down the shaft and capable of movement independently of the car, means 20 on the car and having a running connection with the said element for receiving motion therefrom when the element is moved to open and close the gate, a shaft door, and means for opening and closing the shaft 25 door by the movement of the said element.

3. The combination of an elevator shaft, a car movable therein, elevator shaft doors, a gate on the car, means in the shaft for opening and closing any of the shaft doors, 30 means on the car for operating the car gate, a cable device connected with the first-mentioned means for actuating the same and having a running connection with the said means on the car, a mechanism for actuating 35 the said device, and a controller operative from the car for throwing the said mechanism into operation.

4. The combination of an elevator shaft, a car movable therein, elevator shaft doors, 40 a gate on the car, means in the shaft for opening and closing any of the shaft doors, means on the car for operating the car gate, a cable device connected with the first-mentioned means for actuating the same and 45 having a running connection with the said means on the car, a mechanism for actuating the said device, and a controller operative from the car for throwing the said mechanism into operation, said mechanism 50 including a device for automatically stopping it when the gates reach open or closed position.

5. An elevator shaft, a car movable therein, a gate for the car, an element extending up and down the shaft and capable of movement independently of the car, a pulley system on the car and having a running engagement with the said element, one pulley of the said system being movable, and 55 means actuated by the movable pulley for opening the said gate.

6. The combination of a shaft, an elevator

car movable therein, a gate for the car, means on the car for opening and closing the gate, means in the shaft and having a 65 running engagement with the said means for actuating the latter in any position of the car, and a device for preventing movement of the car while the said gate is open.

7. The combination of an elevator shaft 70 having door openings, doors therefor, a car movable in the shaft, means in the shaft and controllable from the car for opening and closing any door, a gate for the car, a cable extending from the top to the bottom of the 75 shaft and including a loop, sheaves around which the loop engages, one of the sheaves being fixed on the car and the other being movable, means for exerting a pull on the cable to move the movable sheave, and 80 means actuated by the movable sheave for moving the gate of the car.

8. The combination of an elevator shaft having door openings, doors therefor, a car movable in the shaft, means in the shaft and 85 controllable from the car for opening and closing any door, a gate for the car, a cable extending from the top to the bottom of the shaft and including a loop, sheaves around 90 which the loop engages, one of the sheaves being fixed on the car and the other being movable, means for exerting a pull on the cable to move the movable sheave, a cable connected with the gate and having one end fixed to the car, and a movable sheave connected with the first-mentioned movable sheave and acting on the last-mentioned cable to operate the gate.

9. The combination of an elevator shaft, a car traveling therein, a gate on the car, 100 a cable extending longitudinally of the shaft and having a loop, sheaves on the car and engageable with the loop to form an operating running connection between the cable and the car, one of the sheaves being movable toward the other to permit a pull to be exerted on the cable, a winding device 105 for extending a pull on the cable, mechanism actuated by the movable sheave for opening the gate, and a controller for the 110 said mechanism, operative from within the car.

10. The combination of an elevator shaft, a car therein, shaft doors, a car gate, means in the shaft for operating the doors and 115 gate, and an electromechanical apparatus disposed outside the shaft and having means extending into the shaft for operative connection with the first-mentioned means.
